(57) **CLAIM**

The ornamental design for a connecting cap for bottle and cup, as shown and described.

DESCRIPTION

FIG. 1 is a perspective view of a connecting cap for bottle and cup showing my new design;

FIG. 2 is a side elevational view thereof;

FIG. 3 is a top elevational view thereof;

FIG. 4 is a bottom plan view thereof; and,

FIG. 5 is a perspective view thereof, showing it in use, the neck of the bottle and the cup showed in dotted lines for environmental purposes only and form no part of the claimed design.
